UNITED STATES PATENT OFFICE.

GEORGE MOORE, OF JOPLIN, MISSOURI.

DENTIFRICE AND FLOSS DISPENSER.

1,050,560.

Specification of Letters Patent.

Patented Jan. 14, 1913.

Application filed May 7, 1912. Serial No. 695,733.

To all whom it may concern:

Be it known that I, GEORGE MOORE, a citizen of the United States, residing at Joplin, in the county of Jasper and State of Missouri, have invented certain new and useful Improvements in Dentifrice and Floss Dispensers, and do hereby declare the following to be a full, clear, and exact description of the invention, such as will enable others skilled in the art to which it appertains to make and use the same.

This invention relates to improvements in dental apparatus, and the object in view is facilitating the supply of dentifrice and floss.

With this and further objects in view, as will in part hereinafter become apparent and in part be set forth, the invention comprises certain novel constructions, combinations and arrangements of parts as will be herein specified and claimed.

In the accompanying drawing,—Figure 1 is a view in side elevation of a dental apparatus embodying the features of the present invention. Fig. 2 is a transverse section therethrough taken on the plane indicated by line 2—2 of Fig. 1, the band being shown in its lowered position. Fig. 3 is a view similar to Fig. 1 of a slightly modified embodiment, the band being seen in section.

Referring to the drawing by numerals, 1 indicates a dispensing container for dentifrice, having any approved type of dispensing cap 2. In the ordinary course of manufacture, can 1 is formed with annular shoulders 3 and 4 produced by the connection of the top and bottom, respectively, to the body of the can or container. A ring 5, preferably in the form of a flat band, surrounds the body of the can, and is slidable along the same, being limited in its sliding movements by the shoulders 3 and 4.

In the length of the can body 1, preferably adjacent the base, is formed an annular groove or depression 6, as by the contraction of the material of the can or otherwise as preferred. Wound about the can, within groove 6, is a supply of dental floss 7, which, when not being dispensed, is kept covered

by band 5, said band being designed to be positioned as indicated in dotted lines in Fig. 1, and in full lines in Fig. 3, to cover the groove 6. A cutter 8 is fixed to the can 1 at a convenient point, and floss unwound from groove 6 is adapted to be passed across or beneath the cutter for being severed, thus facilitating dispensing appropriate lengths for use.

In operation, the band 5 being closed over groove 6, the operator slides the band upwardly, and grasps the loose end of the floss and unwinds a sufficient supply thereof, either by revolving the can or unwrapping the floss, cuts the floss off across the cutter 8 and then slides band 5 back again over the floss to protect it against foreign substances.

In Fig. 3, I have illustrated a slight variation, comprising providing the can 1' with an annular, reduced portion 9 for accommodating and limiting movements of the band 5', which is adapted to slide to and from a position covering groove 6' and its contained floss 8'. The structure seen in Fig. 3 is operated just the same as that described above. The annular shoulders at the limits of the reduced portion 9 control the extent of play or sliding movement of the band 5'.

What I claim is:

1. In dental apparatus, the combination with a dentifrice container having spaced shoulders, and having that portion of the body of the container between said shoulders formed with an annular groove or recess, adapted to contain a supply of dental floss, and a ring slidably mounted on the body of said container between the shoulders, said ring being of a size to be limited in its movement by said shoulders, the said ring being adapted to be slid to and from a position closing said groove or recess.

2. In dental apparatus, the combination of a dental powder can having a body of annular form, a portion of the body having a reduced diameter forming shoulders at the termini of the reduced portion, the body of the can being formed in the length of the reduced portion with a circumferential groove

adapted to receive a supply of dental floss, and a ring slidably mounted on the reduced portion, and adapted to be moved to and from a position surrounding the groove, said 5 ring being of less diameter than the diameter of the portions of the body of the can outside of the reduced portion.

In testimony whereof I affix my signature in presence of two witnesses.

GEORGE MOORE.
